DESIGN FOR A NAPKIN DISPENSER

Austin E. Cofrin, Green Bay, and Samuel N. Hope, Wauwatosa, Wis., assignors to Fort Howard Paper Company, Green Bay, Wis., a corporation of Wisconsin

Application June 28, 1946, Serial No. 131,144

Term of patent 7 years

(Cl. D44—24)

To all whom it may concern:

Be it known that we, Austin E. Cofrin and Samuel N. Hope, citizens of the United States and residents of Green Bay, in the county of Brown and State of Wisconsin, and of Wauwatosa, in the county of Milwaukee and State of Wisconsin, respectively, have invented a new, original, and ornamental Design for a Napkin Dispenser, of which the following is a specification, reference being had to the accompanying drawing, forming a part thereof.

In the drawing—

Fig. 1 is a perspective view of the dispenser embodying the design.

Fig. 2 is an end elevation of the dispenser.

Fig. 3 is a side elevation of the dispenser; and Fig. 4 is a plan view looking down from the top. We claim:

The ornamental design for a napkin dispenser, substantially as shown.

AUSTIN E. COFRIN.
SAMUEL N. HOPE.
